UNITED STATES PATENT OFFICE.

EDWARD C. WADE, OF NASHVILLE, TENNESSEE.

DESIGN FOR A CHIMNEY-CAP.

40,236.

Specification for Design. Patented Aug. 24, 1909.

Application filed May 15, 1909. Serial No. 496,328. Term of patent 14 years.

To all whom it may concern:

Be it known that I, EDWARD C. WADE, a citizen of the United States, residing at Nashville, in the county of Davidson and State of Tennessee, have invented a new, original, and ornamental Design for Chimney-Caps, of which the following is a specification, reference being had to the accompanying drawing, forming part thereof.

The figure is a perspective view of a chimney cap showing my new design.

I claim:

The ornamental design for a chimney cap, as shown.

EDWARD C. WADE.

Witnesses:

LEE S. RAMSEY,
KNOX KINNARD.
